APPARATUS FOR PRODUCING PLASTIC SURFACES ON WOOD

Wilhelm Cleff, Sackingen, Germany

Application May 25, 1936, Serial No. 81,785
In France June 3, 1935

2 Claims. (Cl. 41—1)

According to the present invention the method of producing plastic surfaces on wood is carried into effect by a device in which, in a single process the wood to be treated is moved by a feeding device, which latter may be instantaneously adjusted to several different speeds, the wood being firstly subjected to the charring effect of a wide burner. After the surface of the wood to be treated has been subjected to the charring or 5 burning effect of the wide burner, said surface in its travel passes a cooling device which acts on the charred surface and affects the heat arising from the charring action before such heat can reach the inner core of the wood which thereby 10 prevents the wood from losing its shape. The cooling device serves at the same time to prevent the discharge of flames and sparks into the decarbonizing and cleaning chamber arranged adjacent thereto. The decarbonization and the 15 production of the plastic variegated wood takes place in the cleaning chamber by means of a number of specially formed quickly rotating grinding rollers arranged one behind the other in the direction of the grain which act on the 20 surface of the wood, such grinding rollers being exactly adjusted or tuned relatively to each other and consisting of rough, medium and fine rollers 25 as well as polishing rollers. The special construction of the grinding rollers also renders possible the decarbonization and fine grinding of 30 slightly chamfered or fluted profiles and of hollow and round boards. The grinding rollers acting in the direction of the grain remove more or less deeply charred parts of the soft wood, and the adjustment of the feed device to a certain 35 speed of rotation more or less helps to give lighter or darker tones. The grain of the wood charred or burned in the carbonizing process remains and stands out in a plastic form from the charred 40 basic surface.

In methods hitherto known for the ornamentation or decoration of wood, in which wood is burned, charred or carbonized, the more or less charred parts of the wood are removed by rubbing with wet cloths or brushes. The burning is 45 done in primitive manner by hand with a soldering lamp in a similar manner to painting with a brush. It is obvious, that by treating the wood in this manner even an expert cannot produce the graduated and uniform tone of colours desired. In other methods, although they give continuous working all parts of the surface are however charred because the same amount of heat 50 is applied for the same length of time, these methods being based on the incorrect principle

that the burning of one surface only would produce stresses in the wood so that it would not remain in its original shape. After this carbonizing process had been effected the surfaces were provided with the desired ornamentation or decoration by brushing, rubbing and so on. 5

The advantage of a variegated surface on one side of the wood only, effected by the plastic treatment of the annual hard concentric rings of growth consists in that the wood is instantaneously and quickly charred by means of a hot flame, the quicker the better, wherein the passage speed of travel of the wood, effected by the feeding device, which is adjustable for different speeds, plays an important part and that immediately afterwards the heat caused by the charring action, before it can penetrate into the core of the wood, is cooled by means of a heat cooling device which thus renders it possible to obtain for panelling and the like purposes 10 straight and non-warping surfaces, the properties of which, as regards warping, are the same as ordinary wood. It is more economical to subject to a charring action one side only of wood used for panelling or like decoration because the treatment of both sides serves no purpose and is un- 15 economical. 20

The accompanying drawing diagrammatically 25 illustrates the device used for carrying said method into effect and wherein:—

Figure 1 shows a longitudinal section of the device; Fig. 1a shows a conventional step pulley which may be adjusted to alter the speed of a feed roller; Fig. 2 shows a cross-section taken on line I—I of Fig. 1; Fig. 3 shows the cross-section of a 30 cleaning and grinding roller; Fig. 4 shows the cross-section of a polishing roller; Fig. 5 shows a comb for a polishing roller. 35

Above the table frame A is arranged a heating or burning chamber B consisting of a casing open at the underside, in which are fitted known types of wide burners 1 equipped with air adjusting means. Behind the burning chamber B is arranged a cooling device C. The latter consists of a water tank 2, the longitudinal side walls 3 of 40 which converge conically towards the bottom leaving an open slot 4 to receive a hygroscopic strip of material or cloth 5 protruding at the outside, such as a cotton wick or the like. The water tank 2, which is supported in a frame 6 secured 45 to the table frame A and pressed downwardly by the springs 7, can be adjusted in height by means of the screw-threaded spindles 8. The distance between the wood to be treated and the outlet of the tank can thus be accurately adjusted. 50 55

Next to this cooling device C, is disposed the de-carbonizing and cleaning chamber D in which are fitted a number of quickly rotating grinding rollers specially constructed for the purpose to which they are to be adapted. The grinding rollers, which are intended for different purposes, can also be lodged individually in separate castings. For their particular purposes, the first rollers 9, which effect the decarbonization, have rougher surfaces than the next following rollers 10 serving for cleaning and grinding and the polishing rollers 11. The cleaning and grinding rollers 10, the bristles of which consist of crimped steel or brass wire, are provided with three equally spaced gaps 12 (Fig. 5) over the circumference. The bristles of the grinding rollers which are subjected to pressure can thus more easily adapt themselves to the shape of the surface to be ground, than would be the case if the bristles entirely covered the roller. The crimped steel or brass wire bristles have the same tearing and grinding effect as sand paper on the surface of the wood so that even profiled parts and hollow boards can be treated perfectly. The circumference of the polishing rollers 11 are provided with a number of equally spaced exchangeable comb-like strips 13 made of leather; rougher or finer combs may be used in accordance with the nature of the surface to be treated. Underneath these grinding rollers, on the table frame A are arranged additional guide rollers 14 for the wood 15 to be treated and in front of the chamber B where the wood enters the machine, as well as behind the cleaning chamber D, where the wood leaves the machine are arranged two mechanically driven feed rollers 16, the number of revolutions of which may be altered in accordance with the time required to treat or char the wood, a scale being provided for adjustment purposes. Thus the degree or intensity of the burning or charring operation most suitable for giving the depth and tone for the different kinds of wood can be determined such as for white or red fir tree, larch or pine and so on. The upper part of the chamber B is provided with a flue 17 in order that the combustion gases may escape and the upper part of the decarbonizing and cleaning chamber is provided with a dome-shaped cover 18 to which is connected a flue 19.

When applying the method by means of the apparatus above described the burners 1 located in the chamber B are first lit. After the device is set going, the wood to be treated is introduced between the two feed rollers 16. The wood then passes through the burning zone 1 in which it is subjected to a uniform heat, the influence of which on the surface of the wood depends on the speed at which the wood is fed along and may be regulated by varying the speed of rotation of the feed rollers 16. After this burning process, the wood reaches the cooling device C which cools the

wood previously heated by the burning or charring action on its surface before the heat reaches the core of the wood so preventing the wood from losing its shape. From the cooling device C, the wood reaches the decarbonizing and cleaning chamber D in which first of all the charcoal dust is removed by means of the first rough grinding roller 9 which dust is drawn away by the flue 19 which forms an extension of the dome-shaped cover 18 and is connected to an exhaust fan or like device. On its further travel, the wood passes through a number of grinding rollers 10, which are arranged one behind the other and exactly adjusted to each other until finally it reaches the polishing rollers 11 which remove all charcoal particles still remaining on the surface of the wood and polish its surface.

I claim:—

1. Apparatus for producing a plastic variegated surface on wood comprising, in combination, a table, a burning chamber mounted on said table, burners mounted in said chamber for charring wood, a cooling chamber containing water mounted on said table in juxtaposition to said burning chamber, an opening in the bottom of said cooling chamber, absorbent material located in said opening, a decarbonizing and cleaning chamber mounted on said table next to said cooling chamber, abrasive and polishing rotary brushes mounted in said cleaning chamber, adjustable means carried by the table at one end for feeding wood along the table, means supporting the wood intermediate the table ends and means at the other end thereof for delivering the wood, the brushes acting on the wood in the direction of the grain.

2. Apparatus for producing a plastic variegated surface on wood comprising, in combination, a table, a burning chamber mounted on said table at one end, regulatable burners mounted in said chamber for charring wood, driven rollers for feeding wood along the table, the speed of said rollers being variable, a cooling chamber containing water mounted on the table in juxtaposition to said burning chamber, an opening in the bottom of said cooling chamber, absorbent material disposed in said opening conducting water to the wood thereunder, a decarbonizing and cleaning chamber mounted on the table in juxtaposition to said cooling chamber, rotary abrasive brushes mounted in said cleaning chamber, the bristles being formed of metal strips, the bristles having equal spaced gaps and a rotary polishing brush mounted in said cleaning chamber, the bristles of said polishing brush being constructed of strips of leather, equally spaced gaps dividing said bristles into groups, said brushes acting on the wood in the direction of the grain.
